UNITED STATES PATENT OFFICE.

JOSEPH DUNNING, OF RUTHERFORD, NEW JERSEY.

COLLAR.

SPECIFICATION forming part of Letters Patent No. 681,114, dated August 20, 1901.

Application filed April 16, 1901. Serial No. 56,103. (No model.)

To all whom it may concern:

Be it known that I, JOSEPH DUNNING, a citizen of United States, residing at Rutherford, in the county of Bergen, State of New Jersey, have invented certain new and useful Improvements in Collars; and I do hereby declare the following to be a full, clear, and exact description of the invention, such as will enable others skilled in the art to which it appertains to make and use the same.

This invention relates to apparel, and more particularly to collars; and the object of the invention is to provide a cheap and simple construction of a collar which will prevent displacement of the necktie and which in the case of a turn-over collar will prevent the points from rolling up.

In the drawings forming a portion of the specification, and in which like numerals of reference indicate similar parts in the several views, Figure 1 is a perspective view showing a turn-down collar embodying the invention. Fig. 2 is a similar view showing a standing collar embodying the invention.

Referring now to the drawings, and more particularly to Fig. 1, it will be noted that the collar has the same shape as the ordinary turn-down collar excepting at the points of the turned-over portion, and at these points there are formed continuations in the shape of fingers 5 and 6. The fingers 5 and 6 are slightly tapered in the direction of their free ends, and the outer or lower edges thereof form continuations of the curvatures of the lower edge of the collar, and these fingers are of such length that when the collar is buttoned in place upon a shirtband the extreme portions of the fingers will overlap. The overlapping portions of the fingers 5 and 6 are provided with buttonholes, and in prac-

tice after the collar is in place an ornamental pin or button is engaged with the buttonholes in these overlapping portions of the fingers. When a necktie is worn with the collar, the body of the tie may lie beneath these fingers and will be held thereby from displacement.

In Fig. 2 of the drawings there is shown a standing collar, at the lower edges of which adjacent to the front are formed fingers 7 and 8, which overlap and are provided with buttonholes positioned to a line to receive the pin or button. A necktie worn with this collar may be passed down and under the fingers and will be held from displacement thereby.

It will be understood that modifications in the specific shape shown may be made without departing from the spirit of the invention, and it will be noted that in each instance the fingers project and lie below the neckband of the collar.

What is claimed is—

A standing collar having tabs provided with buttonholes to receive the front collar-button of a shirt and having portions extending below the tabs with their adjacent edges diverging downwardly, said downwardly-extending portions having fingers extending toward each other and formed to overlap, said fingers having buttonholes and adapted to lie over a necktie passed around the collar and between the diverging edges.

In testimony whereof I hereunto sign my name, in the presence of two subscribing witnesses, on the 4th day of March, 1901.

JOSEPH DUNNING.
